UNITED STATES PATENT OFFICE.

STEPHEN P. M. TASKER, OF PHILADELPHIA, PENNSYLVANIA.

MANDREL.

SPECIFICATION forming part of Letters Patent No. 331,570, dated December 1, 1885.

Application filed June 18, 1885. Serial No. 169,052. (No model.)

To all whom it may concern:

Be it known that I, STEPHEN P. M. TASKER, a citizen of the United States, residing in the city and county of Philadelphia, and State of 5 Pennsylvania, have invented an Improvement in Mandrels for Use in the Manufacture of Metal Tubes, of which the following is a specification.

My invention relates to the class of mandrels 10 which are known as "roller-mandrels," and which are provided with ellipsoidal friction-rolls mounted in bearings in a stock or case, such a mandrel having been invented by me and patented to me in and by Letters Patent 15 of the United States No. 151,323, dated May 26, 1874.

The intention of the employment of a mandrel of the foregoing class is to obviate friction between the interior surfaces of the tube 20 and the ball of the mandrel, and to permit of the more ready passage of the tube over the mandrel, and withdrawal of the mandrel from the tube.

My present mandrel is an improvement 25 upon that patented to me.

A device employing three rolls and embodying a good form of my improvements is represented in the accompanying drawings, and described in this specification, the particular 30 subject-matter claimed as novel being herein-after definitely specified.

In the accompanying drawings, Figure 1 is a top plan view of a mandrel conveniently embodying my improvements and having 35 three rolls. Fig. 2 is a front or face view of the same. Fig. 3 is a rear view of the same, or a view from behind of the socket into which the mandrel-rod is entered. Fig. 4 is a central vertical front elevation, section being 40 supposed in a vertical plane projected on the dotted line x x of Fig. 1—that is to say, in the common plane of the axes of the rolls. Fig. 5 is a central vertical front elevation of a mandrel conveniently embodying my improvements 45 and having four rolls. Fig. 6 is a similar view of a mandrel likewise conveniently embodying my improvements and having five rolls.

In the first four figures similar letters of 50 reference indicate corresponding parts.

Referring now to the first four figures of

the drawings, A A' A² are three ellipsoidal metal rolls mounted in a stock or mandrel-head preferably composed of as many sections as there are rolls, and it is to be understood 55 that three, four, or more rolls may be employed without departure from my invention. The stock represented in the said first four figures of the drawings is, however, formed of three sections, B B' B², which are conveniently connected together by flanges b b' b², which are adapted to be united by bolts C. The body of each section is conveniently a segmental rounded-surfaced arm, to which the letters B B' B² are applied, and when the three sections are united, as they are represented as 60 being in the drawings, they form a spherical skeleton shell or mandrel-head, the circle of which, considered with reference to a central vertical diametric plane, is coincident with 65 the common plane of the axes of the rolls, and in effect completed by the peripheries of the rolls, as shown in Figs. 2, 3, and 4. Each of the rolls is, as stated, ellipsoidal, spherical, or ovoid—their axes all lie in or close to a 70 common plane—and at each of its extremities each roll is mounted or journaled with respect to the sections of the stock by means of journals or axles D, which may either be formed upon the rolls or, as represented in the drawings, formed upon or connected with the sections of the stock. The sections are prolonged to the rear to circumscribe a socket, E, for the mandrel-rod, upon which the mandrel as an entirety is mounted, and by which it is 75 actuated. Each roll, as a reference to Fig. 4 will clearly show, has or may have at or near each of its ends a point of contact with the two adjacent rolls, from which it results that the pressure upon the rolls when the tube is 80 caused to pass over the mandrel is resisted more perfectly than would be the case were the whole pressure exerted upon the journals, and the journals themselves thereby relieved. It is, as stated, possible to employ a greater 85 number of rolls than three, in which case of course the sections of the stock are correspondingly increased in number.

In Fig. 5 of the drawings I have represented the mandrel as provided with four rolls, and in Fig. 6 as provided with five rolls. These forms are not such as I prefer; but they are 90

clearly within my invention, and for such reason illustrated. The shape and configuration of the rolls, as well as the outer surfaces of the sections of the stock, may, moreover, be 5 made to correspond to the interior configuration of tubes which are not cylindriform.

The mandrel is, in connection with external rolls or dies, adapted for use in the manufacture of all kinds of malleable metal tubes from 10 either hot or cold metal. It will be observed that the bellied portions of the sections of the stock lie below the circle circumscribing longitudinally the three rolls, and this is important, because the sections are not intended to 15 bear against the bore of the tube.

In the use of the mandrel it will be understood that after the tube has been rolled it must be rotated to bring that portion of its interior surface which in the previous pass has 20 come over the sections of the stock over the centers or rolling-surfaces of the rolls, and that this operation may be repeated as often as desirable, or until the tube as to every part of its interior surface has been acted upon by 25 the rolls. It is also obvious that the sectional construction of the stock permits me to readily introduce the rolls and remove them for repair or renewal.

I am aware that roller-mandrels having 30 three or more rolls the axes of which do not lie in or close to a common plane, but are approximately parallel with each other and with the axis of the tube through which they operate, have heretofore been known. I do not 35 lay any claim, therefore, to the use of the rolls, except as herein described—that is to say, when their axes lie in or close to a common plane, and are transverse or right angular to rather than parallel with the axis of the 40 tube—and except as provided with bearings at their extremities, as opposed to being simply laid in suitably-shaped sockets.

Having thus described my invention, I claim—

45 1. A mandrel for rolling metal tubes, consisting of three or more ellipsoidal rolls, the axes of which lie in or close to a common plane, in combination with and mounted by bearings at their extremities in a stock or frame.

50 2. A mandrel for rolling metal tubes, consisting of three or more ellipsoidal rolls, the axes of which lie in or close to a common plane, in combination with and mounted by

bearings at their extremities in a sectional 55 stock or frame, substantially as and for the purposes set forth.

3. A mandrel for rolling metal tubes, consisting of three or more ellipsoidal rolls having bearings at their extremities, suitably 60 mounted in a sectional stock or case, with all of their axes in or close to the same plane, but with the axis of each roll at an angle to the axes of adjacent rolls, substantially as and for the purposes set forth.

4. A mandrel for rolling metal tubes, consisting of the combination of three or more rolls having bearings at their extremities, a stock or frame consisting of as many sections as there are rolls, and means for uniting the 70 sections, substantially as and for the purposes set forth.

5. In a roller-mandrel, the combination of three or more ellipsoidal rolls with a sectional case composed of a number of curved 75 sections corresponding in number with the rolls, and provided with flanges whereby the said sections may be united, substantially as and for the purposes set forth.

6. The combination, in a roller-mandrel, of three or more ellipsoidal rolls, a sectional case composed of a number of curved sections corresponding in number with the rolls and provided with flanges, and bolts for uniting the 80 flanges of the sections, substantially as and 85 for the purposes set forth.

7. The combination, in a roller-mandrel, of three or more ellipsoidal rolls, a series of segmental sections containing the bearings for the rolls, and interposed between the extremities 90 of said rolls, and suitable means for uniting the said sections together, substantially as set forth.

8. In a roller-mandrel, the combination of a stock composed of a series of segmental sections adapted to contain the bearings of the rolls and to be interposed between the extremities of said rolls, means for uniting the 95 said sections together, and a series of ellipsoidal rolls corresponding in number to the 100 number of the sections of the stock, substantially as and for the purposes set forth.

In testimony whereof I have hereunto signed my name this 16th day of June, A. D. 1885.

STEPHEN P. M. TASKER.
In presence of—

J. BONSALL TAYLOR,
F. NORMAN DIXON.
